Specification for Design.

Patented Nov. 8, 1921.

Application filed October 11, 1920. Serial No. 416,271. Term of patent 14 years.

To all whom it may concern:

Be it known that I, ROBERT SPENCER, a citizen of the United States, and resident of South Orange, county of Essex, and State of New Jersey, have invented a new, original, and ornamental Design for Easels, of which the following is a specification, reference being had to the accompanying drawing, forming part thereof.

The drawing shows my easel in perspective.

I claim:

The ornamental design for an easel, as shown.

ROBERT SPENCER.
